(57) **CLAIM**

The ornamental design for a waste basket, as shown and described.

DESCRIPTION

FIG. 1 is a perspective view of a waste basket showing my design;

FIG. 2 is a front elevational view thereof;

FIG. 3 is a rear elevational view thereof;

FIG. 4 is a left elevational view thereof, with the right elevational view being a mirror image;

FIG. 5 is a top plan view thereof;

FIG. 6 is a bottom plan view thereof;

FIG. 7 is another perspective view of the waste basket, with a cover of the waste basket rotated 90 degrees; and,

FIG. 8 is a top section, cross sectional view taken along section line 8-8 of FIG. 5.
